Inventor,
George W. Humphreys,
By Frank A. Ahlmann,
Attorney

UNITED STATES PATENT OFFICE.

GEORGE W. HUMPHREYS, OF KANSAS CITY, MISSOURI.

CURTAIN-ADJUSTER.

1,325,401.

Specification of Letters Patent.

Patented Dec. 16, 1919.

Application filed October 15, 1919. Serial No. 330,776.

To all whom it may concern:

Be it known that I, GEORGE W. HUMPHREYS, a citizen of the United States of America, and resident of Kansas City, in

5 the county of Jackson and State of Missouri, have invented certain new and useful Improvements in Curtain-Adjusters, of which the following is a specification.

This invention relates to brackets for 10 shade rollers and particularly to means for supporting a shade roller and to novel means for rotating the roller for the purpose of unwinding or winding the shade with relation to the said roller.

15 An object of this invention is to provide a novel casing with a rotatable member mounted therein and having a projecting spindle adapted to engage a fixture of the shade roller, whereby the movement of the 20 rotating member may be communicated to the said roller.

A still further object of this invention is to provide flexible members coöperating with a drum, the said drum being mounted 25 in a casing so that the drum may be rotated in different directions by a pull on the flexible members.

30 A still further object of this invention is to provide novel means for frictionally retaining the parts against movement when a predetermined adjustment has been attained.

35 With the foregoing and other objects in view, the invention consists in the details of construction, and in the arrangement and combination of parts to be hereinafter more fully set forth and claimed.

40 In describing the invention in detail, reference will be had to the accompanying drawings forming part of this specification 45 wherein like characters denote corresponding parts in the several views, and in which—

Figure 1 illustrates a perspective view of a fixture embodying the invention;

45 Fig. 2 illustrates a vertical sectional view thereof; and

Fig. 3 illustrates a rear view showing the bracket attached to the casing.

In these drawings 5 denotes a casing having 50 a bracket 6 with apertured ears 7 and 8 through which the fastenings may be applied to hold the casing in position.

A plate 9 has an aperture 10 and the said 55 plate is located in the casing and constitutes a bearing for the spindle or shaft 11 and the said member 11 has a projecting end 12

which is angular in cross section to engage a fixture of a roller so that when the member 11 is rotated the shade roller will likewise be rotated.

60 The spindle or shaft 11 to be hereinafter termed a spindle, has drums 13 and 14 mounted on it within the casing and the said drums are separated by a plate 15 which projects beyond the drum to form a flange to 65 confine the flexible members 16 and 17, the former of which is wound on the drum 13 and the latter of which is wound on the drum 14. The flexible members project through the apertures 18 and 19 respectively 70 in the casing and the member 16 is wound on the drum 13 in an opposite direction to that of the winding of the flexible member 17 so that a pull exerted on one of the flexible members will rotate the spindle 11 in 75 one direction, whereas a pull on the other flexible member will rotate the spindle in the opposite direction, and of course, one flexible member will be rewound while the flexible member under tension is being unwound.

80 A bearing plate 20 is held in the casing by the cap or closure 21 which latter has a flange 22 which engages the outer surface of the casing and frictionally retains the cap 85 or cover in place, thereby holding the bearing plate so that the spindle will be rotatably mounted in the casing.

85 The flange 22 has a recess or notch 23 which is adapted to align with the aperture 90 19 to permit the free movement of the flexible member 17, but if it is desired to set the device so that it cannot be readily moved or so that it cannot be accidentally moved, the cap or cover is partially rotated so that 95 an edge of the notch binds against the flexible member with sufficient friction to retard the movement, thereby holding the drum against rotation.

90 As the fixture can be made by the stamping process as to the bracket, casing, cap and bearing plates, the said fixture may be inexpensively produced as it will of course prove durable on account of the fact that there are no parts which are subjected to undue wear.

100 I claim—

1. In a fixture for curtain rollers, a casing, a bracket attached thereto, a cover for the casing having a flange, the said casing having apertures, a spindle, means for rotatably 110 mounting the spindle in the casing, the said spindle projecting through the cover and

- having a projecting end angular in cross section for connection to a curtain roller, drums mounted to rotate with the spindle, a plate on the spindle holding the drums in spaced relation to each other and having its periphery extending beyond the peripheries of the drum, flexible members wound oppositely on the drums and held apart by the said plate, the said flexible members projecting through the apertures of the casing.
2. In a fixture for curtain rollers, a casing, a bracket attached thereto, said casing having apertures in its side, a cover for the casing having a flange with a notch therein adapted to align with one of the apertures

of the casing, a spindle, means for rotatably mounting the spindle in the casing, the said spindle projecting through the cover and having a projecting end angular in cross section for connection to a curtain roller, drums mounted to rotate with the spindle, a plate on the spindle holding the drums in spaced relation to each other and having its periphery extending beyond the peripheries of the drums, flexible members wound oppositely on the drums and held apart by the said plate, the said flexible members projecting through the apertures of the casing.

GEORGE W. HUMPHREYS.
